UNITED STATES PATENT OFFICE.

HENRY A. ROWLAND, OF BALTIMORE, MARYLAND, ASSIGNOR TO THE ROWLAND TELEGRAPHIC COMPANY, OF BALTIMORE, MARYLAND, A CORPORATION OF NEW JERSEY.

SYNCHRONOUS TELEGRAPH SYSTEM.

SPECIFICATION forming part of Letters Patent No. 691,667, dated January 21, 1902.

Application filed February 24, 1899. Serial No. 706,729. (No model.)

To all whom it may concern:

Be it known that I, HENRY A. ROWLAND, a citizen of the United States, residing at Baltimore city, in the State of Maryland, have invented certain new and useful Improvements in Synchronous Telegraph Systems, (Case D;) and I do hereby declare the following to be a full, clear, and exact description of the invention, such as will enable others skilled in the art to which it appertains to make and use the same.

This invention relates to improvements in synchronous telegraphy, and more especially to improvements in or relating to means for obtaining synchronous or steady motion and operating local telegraphic apparatus.

According to the system of telegraphy shown and described in my patent applications, Serial No. 589,352, filed April 27, 1896, and issued as Patent No. 622,636, dated April 4, 1899, and Serial No. 646,017, filed July 26, 1897, the current-distributing apparatus, such as local sunflower devices, as well as other apparatus adapted to rotate in synchronism, are regulated by electrically-controlled synchronizing devices, and these synchronizing devices are regulated either by passing the line signaling-current directly through them or by operating them upon a local low-potential circuit relayed from the main-line current—as, for example, a battery-current having its polarity changed by a main-line relay.

It has hitherto also been my practice, according to the applications above referred to, to operate the local selecting-relays either upon a local battery-circuit separate from the synchronizing-circuit in the main line with the synchronizer (a method shown in the Patent No. 622,636) or upon a local relayed battery-circuit.

The present invention, however, does not contemplate the employment entirely of any of the foregoing methods, but is designed rather as an improvement thereon, whereby I am enabled by the use of condensers or resistances, or both, and the proper arrangement of the local circuits to employ a local dynamo-current of one hundred volts, for example, and use this current for both synchronizing devices and local selecting-relays.

By the invention herein described I can readily use the Edison one-hundred-and-ten-volt circuit where such an arrangement as the connections for changing the polarity of a battery-circuit could not be employed. On 55 a three-wire system, however, the latter method may be used.

This invention comprises also a damper for damping the oscillatory variations from a steady motion, herein shown as operating in conjunction with the synchronizing device and rendering possible a more perfect synchronism. This damper, however, is by no means limited to such specific use, as it may be used in conjunction with almost any piece 65 of rotating mechanism for the purpose of steadyng its motion.

This invention, moreover, comprises means for producing synchronous motion by the use of one or more condensers or their equivalents for any purpose for which the said synchronous motion may be used.

My said invention also embodies a special form of line polarized relay, a special arrangement of the synchronizing device proper differing somewhat from that shown in my prior applications, and other improvements herein-after more particularly described and claimed.

In order to more fully describe my present invention, reference will be had to the accompanying drawings, in which—

Figure 1 is a diagram indicating the arrangement of the circuits and a part of the apparatus embodying my invention. Fig. 2 is a diagrammatic perspective view of my improved line polarized relay. Fig. 3 is a diagram showing one method of connecting the coils of the said relay. Fig. 4 is a diagrammatic perspective view showing the arrangement of the synchronizing device, driving-motor, damper, and selecting-commutator or sunflower device. Fig. 5 represents a central vertical sectional view of one form of the viscous damper. Fig. 6 is a diagram showing a method of operating the synchronizing device differing from that shown in Fig. 4. Fig. 7 is a diagram showing the connections for substituting resistances for the condensers shown in Fig. 1, and Fig. 8 is a diagram showing a method of producing the local synchronizing 95 devices and local selecting-relays.

nizing-current by replacing the line polarized relay by a neutral relay and employing only one condenser.

Referring first to Fig. 1, which represents the connections and apparatus at one station or as much thereof as relates directly to the present invention, L represents a main-line conductor upon which is impressed an alternating or other periodically-varying electro-motive force; A, a main local circuit upon which a continuous direct electromotive force is impressed of, for example, one hundred volts, and B and C shunts connected across the said main local circuit. The shunt B includes resistances b^3 b^3 and b^4 b^4 of, for example, one hundred and two hundred ohms, respectively, while in the shunt C are connected in series the condensers M and M'.

E represents the conventional sunflower of synchronous telegraphs, especially such as used with the inventions described in the aforementioned applications, and H represents selecting-relays connected in the segment-circuits of said sunflower. The trailer F of this sunflower is electrically connected to the shunt-circuit B at some point between the resistances b^4 b^4 , as at b^2 , while the segment-circuits unite and are connected to the tongue k of a relay K. The coils of this relay K are traversed by the main-line current and its contacts k' and k^2 connected to points in the shunt B between the resistances b^3 and b^4 , as at b and b' . The tongue k of the relay K is vibrated by the line-current in unison with the periodic variation thereof, and the trailer F passes over one of the segments of the sunflower for each of said variations or alternations or for one or more of said alternations, the said trailer moving in synchronism with the vibrations of said relay and with the line-current. As the trailer F moves from the center of one conducting-segment to the center of the next the relay-tongue k vibrates from contact k' to k^2 , thus causing a current in one direction to traverse the segment-circuit e and the selecting-relay H connected therein and a current in an opposite direction to traverse the segment-circuit e' , and so on through the series. In this way by the proper adjustment of the resistances in the circuit B enough current from the circuit A will leak or flow through the circuit B to operate the selecting-relays. The object in causing the said selecting-relays to be traversed each normally by currents of the same polarity, but adjacent relays by currents of opposite polarity, is to operate local printing apparatus, which, forming no part of the present invention, need not be here described.

6c The present invention so far as its relation to the relay-circuits is concerned consists in the novel arrangement whereby the said relays may be operated upon a comparatively high potential direct-current circuit.

65 At some point in the circuit C between the condensers M and M', I connect a conductor N and connect in series with this conductor

the regulating-coils P' of a synchronizer or synchronizing device P. The circuit through these coils then passes to the tongue k^3 of the main-line relay, which tongue is vibrated in unison with the line-current, as described relative to the relay-tongue k. The tongues k and k^3 are in practice parts of the same relay, as will be hereinafter shown, but may obviously be upon separate relays, as represented. The tongue k^3 vibrates between contacts k^4 and k^5 , connected in the main local circuit, the latter being provided with resistances A' and A^2 to prevent sparking at said contacts.

By the alternate charging and discharging of the condensers M and M' as the relay-tongue k^3 vibrates between its contacts an alternating current in approximate phase with the main-line current or of any phase bearing a fixed relation to the line-current is sent through the regulating-coils P' of the synchronizing device. The principle of this synchronizing device is substantially the same as the synchronizer shown and described in the Patent No. 622,636, hereinbefore referred to. In each case the device consists, broadly, of a set of coils traversed by a regulating-current of a periodically-varying character rotating in a magnetic field and driven by an independent source of power. The regulating action depends upon the phase relation between the current generated by the regulating-coils of the synchronizing device and the alternating current sent through them from some outside source, as from the condensers, by the vibration of the relay-tongue or its equivalent. If the two currents differ one hundred and eighty degrees in phase and are of the same strength, no current will flow in the regulating-coils of the synchronizer, and hence they will do no work; but when the two currents are in phase the said coils will carry a maximum load. Between these two extremes there are an infinite number of degrees of load which the coils of the synchronizing device will carry and a corresponding number of speeds, the speed varying as the load varies and the load varying as the phase relation between the above-mentioned currents varies, thus maintaining synchronism. This synchronism may be considered as being maintained with relation either with the vibrating tongue of the relay or its equivalent or with regard to the device which generates the current in the circuit which operates the relay. The specific use of this synchronizing device in telegraphy is to drive the sunflower-trailer F, for example, in synchronism with some other trailer; but it must be understood that this means for producing synchronous motion is not confined to such specific uses. The term "synchronizing device" is employed in its broadest sense. In other words, the term "synchronizing device" herein employed designates either the specific device shown or any equivalent thereof, whether of the same size or larger or smaller.

The same result may be accomplished by substituting the resistance $T T'$, as shown in Fig. 7, for the condensers. Otherwise the connections are the same; but it will be noted that I do not confine myself to the use of a polar-line-relay alone, for it will be seen that the desired result may be accomplished with either polar or neutral relay, and in both cases I may employ either one or two of the contacts.

In Fig. 8 I have shown a neutral relay K' replacing the polar relay K and have shown only one condenser connected in the synchronizing-circuit. The relay-tongue k^{00} will be kept in a state of vibration between the contacts k^0 and k^{00} , and when it makes contact at k^0 the condenser M will charge and a current pass through the synchronizing device P in the direction of the lower arrow. When the tongue returns to the contact k^{00} , the condenser will discharge and the current will pass through the synchronizing device in the direction of the upper arrow or in an opposite direction, thus producing the same effect as described in connection with Fig. 1, except that the period of vibration of the tongue k^{00} will be twice as great as that of the tongue k^0 in Fig. 1.

In my prior applications I show the rotatable coils of the synchronizing device mounted on the armature of the driving-motor; but for many reasons the arrangement shown in Fig. 4 is preferable. There the coils P' of the synchronizing device P are separated from the armature Q' of the continuous-current motor Q , though they are both mounted on the same shaft or connected shafts.

The synchronizing device P in this case consists, among other parts, of a plurality of coils P' , the number depending upon the speed required, mounted fast on a rotatable shaft R and supplied with current at the collector-rings $p p$. These coils P' revolve in front of the stationary electromagnets P^2 , which are in this case excited by a continuous current, though it will be hereinafter shown that obviously this arrangement may be changed. The direct-current motor Q drives the shaft R , which is geared or otherwise connected so as to drive the brush F . In this case it is shown geared by a small pinion r to a toothed disk r' , to which is secured the brush-holder f . It may be stated that other motive power than a direct-current motor could be used, if desired.

It will be obvious to any one skilled in the art that the same result may be obtained by the synchronizing device whether I employ the arrangement shown in Fig. 4 or whether an alternating current is caused to excite the magnets P^2 and a direct current caused to pass through the moving coils P' . Also an alternating current could be made to pass through both coils and magnets, and it is likewise obvious that either magnets or coils may be made to rotate without affecting the principle of the device. It will furthermore be

noted that I may substitute for the moving coils P' the permanent magnets P^3 of Fig. 6 and the same result will be accomplished, in which case the magnets P^2 would be excited by an alternating current; nor would the effect vary were the magnets P^3 soft iron instead of permanent magnets, although in the latter case the speed may be half or made greater in the proportion two, three, four, &c. This arrangement will within reasonable limits cause the shaft R to rotate in synchronism with the line-current; but I insure a more perfect synchronism by employing the damper S in conjunction with the synchronizing device P .

In Fig. 4 the damper shown is an oil-damper and partly mounted on the same shaft R with the synchronizing device and consists of a flattened cup or oil-receptacle S' , closed back and front and mounted fast upon the shaft R' . Within the cup is mounted a flanged disk S^2 upon a sleeve s , which is secured fast to the shaft R and extends through one face of the cup S' .

S^3 represents the oil or other suitable liquid surrounding the disk and which may be poured into the receptacle through a plug-opening or in any other suitable way. The cup-shaped portion s' of the receptacle catches the oil which tends to escape along the collar and allows it to flow back into the receptacle through the aperture s^2 .

The action of the damper is as follows: As the shaft R rotates the disk S^2 will rotate with it and, acting through the oil, will drag the receptacle S' along with it until the said receptacle attains a speed equal to that of the disk. Then should the disk tend to diminish its speed the receptacle, by virtue of its inertia and being mounted loosely with respect to the shaft R , will drag the disk along and cause it to catch up. On the other hand, when the disk S^2 exceeds its normal speed the oil-receptacle, acting through the oil, will drag it back to normal speed. It must be understood, however, that the action of the damper is to prevent such oscillations as above referred to by deadening the variations from the actual steady motion—that is to say, the true function of the damper is to prevent these oscillations from taking place in the first instance rather than waiting until after the oscillation has occurred to correct it. The shaft R may extend all the way through the damper instead of only a portion of the way through it, as shown, and the cup S' loosely mounted thereon; but this oil-damper is only one form of damper embodying my general principle—viz., producing a damping effect between two revolving parts through a viscous medium.

This viscous damping effect may be produced by a magnetic field and many other ways, and I use the word "viscous" in its broad or generic sense.

In Fig. 2 are shown the essential parts of my improved form of polarized relay. This relay K is provided with two tongues k and k^0 , the tongue k being mounted on a hollow sleeve

*k*⁶ and the tongue *k*³ upon the spindle or rod *k*⁷, which is inclosed by the sleeve *k*⁶. These supports of the relay-tongues are pivoted in any convenient manner, so as to be revoluble 5 to a limited extent around their longitudinal axes. The tongues *k* and *k*³ are provided with metallic contact-strips *k*⁸ and *k*⁹, respectively, which vibrate between the contacts *k*¹ *k*² and *k*⁴ *k*⁵ respectively. These metallic strips *k*⁶ 10 and *k*⁹ are insulated from the tongues, as at *k*⁰. The same relay-coil *K*' surrounds or operates both tongues and may be wound in the ordinary way, as shown in Fig. 2, or it may be wound in sections, as shown in Fig. 3. In 15 the latter case the coil is made up of, for example, five sections *k*¹⁰, *k*¹¹, *k*¹², *k*¹³, and *k*¹⁴. These sections are so wound that the three central sections contain the same number of turns, while the end sections contain the same 20 number of turns as each other, but only half as many as the central sections, and the two end sections *k*¹⁰ *k*¹⁴ and central section *k*¹² are connected together, while the two intermediate sections *k*¹¹ and *k*¹³ are connected together. 25 By this means a more complete balance is obtained than could otherwise be done in case a duplex arrangement is needed.

The line-current traversing the coils of the relay *K* will cause both tongues *k* and *k*³ to 30 vibrate between their stops, and while in their action they are independent of one another they are both actuated by the same cause. In saying that these relay-tongues are independent it is to be understood that 35 they are independent to this extent: that if one is held stationary the others may continue to vibrate; but in practice it is preferable to have just enough friction between the spindle *k*⁷ and sleeve *k*⁶ to cause one tongue 40 to drag the other if neither is held stationary and the operating force is applied to one only.

The relays *K* can be both polar relays or neutral ones, or one may be a polar relay and the other a neutral relay. They may be separated or combined.

Having thus fully described my present invention, what I claim, and desire to secure by Letters Patent of the United States, is—

1. The combination with a synchronizing 50 device, of a plurality of condensers, said condensers being connected in circuit with said synchronizing device, and means for causing said condensers to alternately discharge through said synchronizing device for regulating the motion of the same, substantially as described.

2. The combination with a synchronizing 55 device, of a condenser, said condenser being connected in circuit with said synchronizing device, and means for causing said condenser to alternately charge and discharge through said synchronizing device for regulating the motion of the same, substantially as described.

3. The combination with a synchronizing 60 device, of a plurality of condensers, said condensers being connected in circuit with said synchronizing device, proper resistances in

said condenser-circuits, and means for causing said condensers to alternately discharge through said synchronizing device for regulating the motion of the same, substantially as described. 70

4. The combination with a synchronizing device, of two condensers, said condensers being connected in circuit with said synchronizing device and means for causing one of said condensers to discharge through said synchronizing device while the other of said condensers is charging and vice versa whereby said synchronizing device is regulated, substantially as described. 75

5. The combination with a synchronizing device, of two condensers, said condensers being connected in circuit with said synchronizing device, proper resistances in each of 85 the condenser-circuits and means for causing one of said condensers to discharge through said synchronizing device while the other of said condensers is charging and vice versa whereby said synchronizing device is regulated, substantially as described. 90

6. The combination with a synchronizing device, of a condenser connected in circuit with said synchronizing device, a relay, a conductor carrying an alternating current and 95 traversing said railway whereby the said condenser is caused to discharge through said synchronizing device, substantially as described.

7. The combination with a synchronizing 100 device, of a plurality of condensers connected in circuit with said synchronizing device, a relay, a conductor carrying an alternating current and traversing said relay whereby the said condensers are caused to alternately discharge through said synchronizing device, 105 substantially as described.

8. The combination with a main-line circuit carrying an alternating electric current, of a main local circuit having a direct electromotive force impressed upon it, a relay having its contacts connected in said main local circuit, condensers in a shunt-circuit, a circuit passing from said shunt-circuit at a point intermediate between said condensers to said relay-tongue and a synchronizing device traversed by the current of the last-named circuit, substantially as described. 110

9. The combination with a main-line wire carrying an alternating electric current, a relay operated by said current, a local circuit carrying a direct current and connected to each of the contacts of said relay, a shunt-circuit connected across said local circuit, condensers connected in said shunt-circuit 115 and a circuit extending from said shunt-circuit at a point intermediate between said condensers to said relay-tongue, substantially as described.

10. The combination with a main-line wire 120 carrying an alternating electric current, a relay operated by said current, a local circuit carrying a direct current and connected to each of the contacts of said relay, a con-

denser connected to one side of said local circuit and to the tongue of said relay, substantially as described.

11. The combination with a conductor carrying an alternating electric current, a relay operated by said alternating current, a local circuit supplied with a direct current, and connected to the contacts of said relay by a proper resistance, condensers connected in shunt with said main local circuit, a conductor connected to the condenser-circuit intermediate between said condensers and connected to said relay-tongue, substantially as described.

12. The combination with two condensers, of a relay having one of its contacts in each condenser-circuit, a conductor connected to the tongue of said relay and to the condenser-circuit intermediate between said condensers, a conductor carrying an alternating current and traversing said relay whereby the said condensers are caused to alternately discharge through the conductor connected to said relay-tongue, substantially as described.

13. The combination with a main-line circuit carrying an alternating electric current, of a main local circuit carrying a direct current, a relay having its contacts connected in said main local circuit, each through a proper resistance, a shunt-circuit connected across said main local circuit, condensers in said shunt-circuit, a circuit passing from said shunt-circuit at a point intermediate between said condensers to said relay-tongue and a synchronizing device traversed by the current of the last-named circuit, substantially as described.

14. In a system of synchronous telegraphy the combination with a main-line circuit carrying an alternating electric current, of a main local circuit carrying a direct current, a relay having its contacts connected in said main local circuit, a shunt-circuit connected across said main local circuit, properly-adjusted resistances in said shunt-circuit, a circuit passing from said shunt-circuit at a point intermediate between said resistances to said relay-tongue and a sunflower and trailer device with its segment-circuits traversed by the current in the last-named circuit, substantially as described.

15. The combination with a conductor carrying an alternating electric current, a relay operated by said alternating current, a local circuit supplied with a direct current and connected to the contacts of said relay by a proper resistance, properly-adjusted resistances connected across said main local circuit, a conductor connected between said resistances and connected to said relay-tongue, substantially as described.

16. In a system of telegraphy, the combination with a conductor carrying an alternating electric current, of a relay operated by said alternating current, a main local circuit carrying a direct current, a shunt-circuit con-

nected across said main local circuit, a branch circuit connected to said shunt-circuit and passing through the contacts of said relay, a sunflower and trailer device having its segment-circuits connected to the tongue of said relay and its trailer connected to said shunt-circuit, substantially as described.

17. In a system of telegraphy, the combination with a conductor carrying an alternating electric current, of a relay operated by said alternating current, a main local circuit carrying a direct current, a shunt-circuit connected through proper resistances across said main local circuit, a branch circuit connected to said shunt-circuit and passing through the contacts of said relay, a sunflower and trailer device having its segment-circuits connected to the tongue of said relay and its trailer connected to said shunt-circuit, substantially as described.

18. In a system of telegraphy, the combination with a conductor carrying an alternating electric current, of a relay operated by said alternating current, a main local circuit carrying a direct current, a shunt circuit connected through proper resistances across said main local circuit, a branch circuit connected to said shunt-circuit and passing through the contacts of said relay, a sunflower and trailer device having its segment-circuits connected to the tongue of said relay and its trailer connected to said shunt-circuit and a plurality of selecting relays connected in said segment-circuit, substantially as described.

19. A damper consisting of two revolving parts one of which is freely moving and connected to the other by viscous damping, substantially as described.

20. The combination with a shaft, the speed of which is to be maintained approximately uniform, of a device for damping the oscillatory vibrations in the motion of said shaft, said device comprising a member mounted to rotate with said shaft, and a second member having inertia and capable of movement relative to said shaft, and damping means connecting the said members.

21. The combination with a source of power, of a synchronizing device driven thereby, a revolving body connected to said synchronizing device and a second revolving body freely moving and connected to the first by means of viscous damping, substantially as described.

22. The combination with a source of power, of a synchronizing device driven thereby, and regulated by an alternating electric current, a revolving body connected to said synchronizing device and a second revolving body freely moving and connected to the first by means of viscous damping, substantially as described.

23. The combination with a synchronous motor, of means for damping oscillatory variations in the speed of the motor-shaft, said means comprising a body mounted to rotate with said shaft and a second body having in-

ertia and capable of movement relative to the first body, and damping means connecting the two bodies.

24. The combination with a source of power, of a synchronizing device driven thereby and regulated by an alternating electric current, a revolving body connected to said synchronizing device and a second revolving body connected to the first by means of viscous damping, substantially as described.

25. The combination with a sunflower and trailer device of a motor operating said device, a synchronizing device driven by said motor and regulated by an alternating electric current, a revolving body connected to said synchronizing device and a second revolving body connected to the first through viscous damping, substantially as described.

26. A damper having a driven revolving body, a freely-moving revolute receptacle inclosing said revolving body, and a liquid inclosed in said receptacle and surrounding the first revolving body whereby motion is transmitted to the receptacle and the vibration of both the revolving body and receptacle are damped, substantially as described.

27. In a damper the combination with a driven disk, of a freely-moving revolute receptacle inclosing said disk, a viscous damping fluid carried by said receptacle and inclosing said disk whereby motion is transmitted to said receptacle from said disk and the vibration of both is damped, substantially as described.

28. In a polarized relay the combination with two relay-tongues mounted upon independent oscillating supports, an exciting-coil surrounding said supports which form the core thereof and independent contacts for each tongue, substantially as described.

29. In a polarized relay the combination with an exciting-coil, of a hollow iron core passing through said coil, a second core passing longitudinally through said hollow core, said cores being revolute about their longitudinal axes independent of each other, a tongue mounted on the hollow core and a tongue mounted on the second core, independent contacts for each of said tongues, substantially as described.

30. The combination with a synchronizing device, of a condenser connected in circuit with said synchronizing device, a relay, a conductor carrying a periodically-varying electric current and traversing said relay whereby the said condenser is caused to discharge through said synchronizing device, substantially as described.

31. The combination with a synchronizing device, of a plurality of condensers connected in circuit with said synchronizing device, a relay, a conductor carrying a periodically-varying electric current and traversing said relay whereby the said condensers are caused to alternately discharge through said synchronizing device, substantially as described.

32. The combination with a main-line cir-

cuit carrying an electric current which periodically varies in intensity, of a main local circuit having a direct electromotive force impressed upon it, a relay having its contacts connected in said main local circuit, a shunt-circuit connected across said main local circuit, condensers in said shunt-circuit, a circuit passing from said shunt-circuit at a point intermediate between said condensers to said relay-tongue and a synchronizing device traversed by the current of the last-named circuit, substantially as described.

33. The combination with a main-line wire carrying a periodically-varying electric current, a relay operated by said current, a local circuit carrying a direct current and connected to each of the contacts of said relay, a shunt-circuit connected across said local circuit, condensers connected in said shunt-circuit and a circuit extending from said shunt-circuit at a point intermediate between said condensers to said relay-tongue, substantially as described.

34. The combination with a main-line wire carrying a periodically-varying electric current, a relay operated by said current, a local circuit carrying a direct current and connected to each of the contacts of said relay, a condenser connected to one side of said local circuit and to the tongue of said relay, substantially as described.

35. The combination with a conductor carrying a periodically-varying electric current, a relay operated by said current, a local circuit supplied with a direct current, and connected to the contacts of said relay by a proper resistance, condensers connected in shunt with said main local circuit, a conductor connected to the condenser-circuit intermediate between said condensers and connected to said relay-tongue, substantially as described.

36. The combination with two condensers, of a relay having one of its contacts in each condenser-circuit, a conductor connected to the tongue of said relay and to the condenser-circuit intermediate between said condensers, a conductor carrying a periodically-varying electric current and traversing said relay whereby the said condensers are caused to alternately discharge through the conductor connected to said relay-tongue, substantially as described.

37. The combination with a main-line circuit carrying a periodically-varying electric current, of a main local circuit carrying a direct current, a relay having its contacts connected in said main local circuit, each through a proper resistance, a shunt-circuit connected across said main local circuit, condensers in said shunt-circuit, a circuit passing from said shunt-circuit at a point intermediate between said condensers to said relay-tongue and a synchronizing device traversed by the current of the last-named circuit, substantially as described.

38. In a system of synchronous telegraphy,

the combination with a main-line circuit carrying a periodically-varying electric current, of a main local circuit carrying a direct current, a relay having its contacts connected in said main local circuit, a shunt-circuit connected across said main local circuit, properly-adjusted resistances in said shunt-circuit, a circuit passing from said shunt-circuit at a point intermediate between said resistances to said relay-tongue and a sunflower and trailer device with its segment-circuits traversed by the current in the last-named circuit, substantially as described.

39. The combination with a conductor carrying a periodically-varying electric current, of a local circuit connected to a source of direct current, properly-adjusted resistances connected across the local circuit, contacts located in said local circuit, a conductor connected to a point between said resistances, and means operated by the periodically-varying current for completing the circuit from said conductor to first one and then the other of said contacts.

40. In a system of telegraphy, the combination with a conductor carrying a periodically-varying electric current, of a relay operated by said current, a main local circuit carrying a direct current, a shunt-circuit connected across said main local circuit, a branch circuit connected to said shunt-circuit and passing through the contacts of said relay, a sunflower and trailer device having its segment-circuits connected to the tongue of said relay and its trailer connected to said shunt-circuit, substantially as described.

41. In a system of telegraphy, the combination with a conductor carrying a periodically-varying electric current, of a relay operated by said current, a main local circuit carrying a direct current, a shunt-circuit connected through proper resistances across said main local circuit, a branch circuit connected to said shunt-circuit and passing through the contacts of said relay, a sunflower and trailer device having its segment-circuits connected to the tongue of said relay and its trailer connected to said shunt-circuit, substantially as described.

42. In a system of telegraphy, the combination with a conductor carrying a periodically-varying electric current, of a relay operated by said current, a main local circuit carrying a direct current, a shunt-circuit connected through proper resistances across said main local circuit, a branch circuit connected to said shunt-circuit and passing through the contacts of said relay, a sunflower and trailer device having its segment-circuits connected to the tongue of said relay and its trailer connected to said shunt-circuit and a plurality of selecting relays connected in said segment-circuit, substantially as described.

43. The combination with a synchronizing device of a damping device acting to damp the

oscillatory variations thereof from a steady motion, substantially as described.

44. The combination with a continuously-moving synchronizing device, of a damping device acting to damp the oscillatory variations thereof from a steady motion, substantially as described.

45. The combination with a revolving mechanism the speed of which is to be maintained uniform, of a damper acting to damp any oscillatory variations from the uniform motion and comprising a plurality of freely-moving members connected by viscous damping, substantially as described.

46. The combination with a revolving mechanism the speed of which is to be maintained uniform, of a damper acting to damp any oscillatory variations from the uniform motion and comprising a plurality of revolving parts, some of said parts being tightly secured to their support and the others loosely fitted thereon, the said tightly and loosely fitted parts being connected through the medium of viscous damping, substantially as described.

47. The combination with an electric motor and a synchronizing device having a steady motion, of a damping device acting to damp the oscillatory variations from said steady motion, substantially as described.

48. The combination with a synchronizing device, of a direct-current electric motor driving said synchronizing device and having a steady motion, and a damper acting to damp the oscillatory variations from said steady motion, substantially as described.

49. The combination with a synchronizing device having a steady motion and whose speed is regulated by a periodically-varying electric current, of a damper acting to damp the oscillatory variations from said steady motion, substantially as described.

50. The combination of a damper, substantially as described, with an electrically-regulated direct-current motor and an alternating-current dynamo acting to synchronize said motor, substantially as described.

51. A telegraph-line, in combination with a local circuit and a source of direct current connected thereto, of means for varying the current periodically in a part of the local circuit, said means comprising a condenser and relay, substantially as described.

52. A telegraph-line, in combination with a local circuit and a source of direct current connected thereto, of means for varying the current periodically in a part of the local circuit, said means comprising condensers and a relay, substantially as described.

53. A telegraph-line carrying an alternating electric current, in combination with a local circuit and a source of direct current connected thereto, of means for varying the current periodically in a part of the local circuit, said means comprising a condenser and relay, substantially as described.

54. A telegraph-line carrying an alternating electric current, in combination with a local circuit and a source of direct current connected thereto, of means for varying the current periodically in a part of the local circuit, said means comprising condensers and a relay, substantially as described.
55. A telegraph-line carrying a periodically varying electric current, a vibrating contact-maker operated by the said current, a local circuit connected to the contacts of said contact-maker, and a condenser connected to one side of said local circuit and to said contact-maker, substantially as described.
56. A telegraph-line carrying a periodically varying electric current, a local circuit having contacts located therein, a conductor vibrated between said contacts, condensers connected across the local circuit, and the vibrating conductor connected between the con-

densers whereby electricity from the condensers only may traverse said conductor, substantially as described.

57. A telegraph-line carrying a periodically varying electric current, a local circuit having contacts located therein, an electric conductor vibrated between said contacts, condensers connected across the said local circuit, and the vibrating conductor connected between the condensers whereby electricity from the condensers only may traverse the said conductor and a synchronizing device regulated by the charging and discharging of said condensers, substantially as described.

In testimony whereof I affix my signature in presence of two witnesses.

HENRY A. ROWLAND.

Witnesses:

W. SCOTT GOSNELL,
DANL. BRIDE.
